US00D397435S

United States Patent [19]

Naumann

[11] Patent Number: Des. 397,435

[45] Date of Patent: **Aug. 25, 1998

[54] COMBINED INHALER AND COVER

DESCRIPTION

[75] Inventor: Peter F. Naumann, München, Germany

FIG. 1 is a perspective view of a first embodiment of the present invention;

[73] Assignee: GGU Gesellschaft fuer
Gesundheits-und Umweltforschung
mbH, Puch-Heim-Muenchen, Germany

FIG. 2 is a top plan view of the first embodiment of the present invention;

[**] Term: 14 Years

FIG. 3 is a front elevational view of the first embodiment of the present invention;

[21] Appl. No.: 73,156

FIG. 4 is a right side elevational view of the first embodiment of the present invention;

[22] Filed: Jun. 30, 1997

FIG. 5 is a rear elevational view of the first embodiment of the present invention;

[30] Foreign Application Priority Data

Jan. 3, 1997 [XH] Hague Agreement 007593

FIG. 6 is a left side elevational view of the first embodiment of the present invention;

[51] LOC (6) Cl. 24-04

FIG. 7 is a bottom plan view of the first embodiment of the present invention;

[52] U.S. Cl. D24/110

FIG. 8 is a perspective view of the present invention, with the cover removed;

[58] Field of Search D24/110; 128/200.23,

FIG. 9 is a top plan view of the second embodiment of the present invention;

128/200.24, 200.25, 200.14, 200.16, 200.18,
203.18

FIG. 10 is a front elevational view of the second embodiment of the present invention;
